United States Patent Office.

LA FORIST ROLLINS, OF BANGOR, MAINE.

Design No. 4,821, dated April 18, 1871.

DESIGN FOR A STOVE.

The Schedule referred to in these Letters Patent and making part of the same.

To all whom it may concern:

Be it known that I, LA FORIST ROLLINS, of Bangor, in the county of Penobscot and State of Maine, have invented and produced a new and original Design for Stoves, of which the following is a specification, reference being had to the accompanying photographic illustration.

My design consists of the arrangement of the moldings around the base, front, and sides of the stove, and around the top and bottom of the same. The legs are also set in under the stove-body.

The doors have moldings surrounding them, and the large doors of the oven have in their centers, surrounded by a circular molding, the seal of the State of Maine.

The small doors of the oven, and also those of the grate and fire-box, are ornamented with the shield of the United States.

The top of the stove projects more than is common in stoves of the size, rendering it more symmetrical.

The name of the stove is placed on the sides, and is also upon the seal and slide-hearth.

The design is fully illustrated by the accompanying photograph, which shows the character of the moldings, &c.

What I claim as my invention, and desire to secure by Letters Patent, is—

The design for a stove, as herein described and shown.

LA FORIST ROLLINS.
